UNITED STATES PATENT OFFICE.

CHARLES JAMES HALE, OF NEW YORK, N. Y., ASSIGNOR TO UNITED STATES METAL PRODUCTS CO., OF NEW YORK, N. Y., A CORPORATION OF MASSACHUSETTS.

METAL FRAME FOR DOORS, WINDOWS, AND THE LIKE.

1,071,911.

Specification of Letters Patent. Patented Sept. 2, 1913.

Application filed September 8, 1908. Serial No. 451,972.

To all whom it may concern:

Be it known that I, CHARLES JAMES HALE, a citizen of the United States, and a resident of the borough of Manhattan, city, county, and State of New York, have invented certain new and useful Improvements in Metal Frames for Doors, Windows, and the Like, of which the following is a specification.

This invention relates to metal frames for doors, windows and the like, and also to means for connecting such frames to the wall in a fireproof manner.

I will describe a preferred embodiment of my invention applied to a door frame and my preferred means of connecting the same to a wall and then point out the novel features in claims.

Figure 1 is an elevation, partially broken away, of one side of a metal door frame embodying my invention and showing position of brace-bars in dotted lines; Fig. 2 is a view partially in horizontal section on the line 2—2 of Fig. 1 and partially in plan of the same; Fig. 3 is a detail view of a preferred form of brace-bars; Fig. 4 is a vertical sectional view of a door frame form, showing my preferred manner of connecting the inner frames to the saddle and to each other; and Fig. 5 is a vertical sectional view of the saddle and connections therewith taken at right angles to Fig. 4.

Similar reference characters designate corresponding parts.

Referring now to the form shown in these drawings, A indicates a door frame having sheet-metal trim. The trim is preferably divided into two sections F and G and is connected to the wall as hereinafter described.

A', Fig. 2 indicates a wall or partition of brick and plaster or other material. The dotted lines 1 and 2 (Fig. 2) are intended to indicate a section of brick between such lines, and sections of plaster on each side thereof as at 3 and 4. Embedded or otherwise secured in the wall A' are metallic anchor-bolts B of any suitable size and form. As shown, these bolts are oblong in form (see dotted lines, Fig. 3) and are provided with threaded heads which project beyond the brick wall at either end to coact with nuts b, b'. A plurality of such anchor-bolts are preferably built into the wall at a plurality of points contiguous to the edge of the opening for the door.

At the junction of the sides and edge of the wall I preferably provide an inner-frame of sheet-metal. As illustrated, this inner-frame comprises two sections C, C' which are each preferably bent longitudinally at substantially a right angle to inclose each corner formed by the edge and sides of the wall, the plaster and brick at such points being preferably cut away to permit the same to be set in flush with the adjacent portions of the wall. They may be continuous and extend completely around the doorway from the saddle on one side to the saddle on the opposite side, or they may be formed in as many separate or separated sections as desired. I preferably employ two continuous inner-frame sections, one for each corner junction of the sides and edge of the wall.

Brace-bars D, D' are preferably secured intermediate their ends in any suitable manner, and, as shown, by the nuts and threads b, b', to the anchor-bolts B. One end of each of such bars are secured by screws e, e' or other suitable means to the inner-frame sections C, C' and tend to hold the same in position against the wall. The bars D, D', after being secured to the inner-frame sections C, C' are preferably bent inwardly, so that the intermediate portions d, d' rest against the brick of the partition, where they are secured to the bolts as aforesaid, and are then bent outwardly near their other ends to form flange portions d², d³, which project at substantially right angles to the wall and preferably extend beyond the face of the plaster thereof.

The holes in the bars D, D' for the reception of the bolts and screws are elongated as shown at b², b³ and e², e³ so as to permit the same bars to be employed for different sizes of trim. The frames C, C' are also further braced and secured in position at suitable points along the edge of the wall by auxiliary braces or distance pieces E, E', which distance pieces at all points along the sides and top of the doorway, excepting the corners, are preferably flat bars or strips of metal and are secured at their opposite ends to the inner-frames C, C' by screws e, e', or in any other suitable manner. At the two upper corners these distance pieces E are angular in form to fit such-corners (see Fig. 4). At the lower corners, (Figs. 4 and 5), such distance pieces are likewise angu-

lar in form, one leg of the angle E', extending beneath the inner-frame sections C, C' and between the same and the saddle J, which as shown, Fig. 5, is a channel arm, 5 and to which the angle E' may be secured by means of the screw and nut *j* or other suitable means. The hole in the saddle J for the reception of the nut-screw *j* is also preferably elongated as at *j'* to permit adjustment and also to allow for expansion under excessive heat. The frames C, C' thus form a convenient metallic securing means for one edge of the trim sections, and the flanged portions *d*², *d*³ of the brace-bars 15 form a convenient securing means for the other edge of such trim. The jamb or trim is formed of sheet metal and is preferably divided into two sections F, G, each bent at substantially right angles to include the 20 edge of the wall and portions of opposite sides thereof. The portions *f*, *f'* of each section which oppose the sides of the wall may be bent to represent molding of the form shown or any other preferred form. 25 I preferably form the portions *f'* of the section F straight, while the portion *g'* of the section G is bent to represent the door stop H which overlaps the portion *f'*.

The sections F and G of the trim may be 30 secured to the inner-frame and brace-bars in any desired manner, and I do not wish to limit myself to the use of the means shown. As illustrated, the portions *f*, *g*, after being bent to form the molding as 35 above described, are bent at substantially right angles to the wall and secured by screws *f*², *g*², to the flange portions *d*², *d*³ of the brace-bars D. Each of said sections F and G are preferably secured to the frame 40 near the edges of the wall by any suitable means, such as the screws *g*³ and *g*⁴, which screws also preferably pass through the distance pieces E. One of said sections preferably overlaps and is secured to the other 45 section at some suitable point, such as near the center of the edge of the door. Any fastening means may be used. I have shown screws *h* which preferably also secure both of said overlapping edges to the 50 distance pieces E. As above stated, the portion *g'* of the section G is bent to represent the door stop H. It is beneath this door stop that I show the two portions *f'* and *g'* connected together and to the distance pieces.

Any other point of connection may be selected, but I prefer to connect the two portions and the distance pieces with a single fastener. 55

Having described my invention, what I claim is:

1. A frame for doors, windows and the like, comprising a wall, sheet metal trim completely covering the edge and extending backward a predetermined distance along each side of the wall, a securing device embedded in the wall, means for connecting the same rigidly at the sides of the wall to the trim, and metallic inner frames extending around each corner of the edge of the wall and rigidly secured both to the aforesaid securing device and to the metal trim. 65

2. A frame for doors, windows and the like, comprising sheet metal trim, a metallic inner frame embracing the edges of the door opening, brace bars therefor, and means for securing the trim to said inner-frame and to the brace bars. 70

3. A frame for doors, windows and the like, comprising a wall, sheet metal trim, metallic anchor bolts embedded in the wall, an inner-frame embracing the corners formed by the junction of the sides and edge of the wall, brace bars connecting said anchor bolts and inner-frame, and means for securing the trim to the inner-frame at the edge of the doorway and to the brace-bars 80 at the sides thereof.

4. A frame for metal doors, windows and the like, comprising a wall composed of brick and a layer of plaster on each side thereof, anchor bolts projecting at each side of the brick only, a sheet metal trim, brace bars at each side of the wall each having an inwardly-bent central portion abutting against the brick of the wall and outwardly-extending end portions extending beyond the plaster, means for connecting the central portion rigidly to the anchor bolt and wall, and means for connecting the trim to said bars at both sides of said central portion. 90 95

In witness whereof, I have signed my name to the foregoing specification in the presence of two subscribing witnesses.

CHARLES JAMES HALE.
